UNITED STATES PATENT OFFICE

157,034

SHOE OR SIMILAR ARTICLE OF FOOTWEAR

James F. Eldon, Melrose, Mass., assignor to Converse Rubber Corporation, Malden, Mass., a corporation of Massachusetts

Application September 18, 1948, Serial No. 148,647

Term of patent 14 years

(Cl. D7—7)

To all whom it may concern:

Be it known that I, James F. Eldon, a citizen of the United States of America, residing at Melrose in the county of Middlesex and Commonwealth of Massachusetts, have invented a new, original, and ornamental Design for a Shoe or Similar Article of Footwear, of which the following is a specification, reference being had to the accompanying drawings, forming a part thereof, of which:

Fig. 1 is a side elevational view of a shoe showing my new design;

Fig. 2 is an elevational view of the opposite side shown on Fig. 1.

The essential features of my design reside in the parts shown in full lines.

I claim:

The ornamental design for a shoe or similar article of footwear, substantially as shown and described.

JAMES F. ELDON.
